UNITED STATES PATENT OFFICE

2,547,488

DOOR AND MECHANISM FOR OPENING AND CLOSING THE SAME

Clyde Potts, Morristown, N. J.; Weston Gavett, Stanley N. Williams, and John D. Collins, 3rd, executors of said Clyde Potts, deceased

Application May 3, 1946, Serial No. 666,997

2 Claims. (Cl. 268—74)

1

The invention relates to the construction of doors and opening and closing mechanism for the same, and while not limited in its application, is specially designed and adapted for use, as herein embodied, for closing the entrance doorway of small airplane hangars.

To enable such a door to be opened and closed with a minimum of power, the door is divided lengthwise into two balanced sections, the upper section being hinged to the top of the doorway to swing outward and upward about a horizontal axis and the lower section hinged to the bottom of the same, to swing outward and downward about a parallel axis. In open position, the upper door section protects the hangar entrance against varying weather conditions and the lower door section ordinarily serves as a ramp to ease the way for an airplane being entered in the hangar.

For opening and closing the door sections, a toggle action, which may be operated by hand but is preferably power-operated, is employed at one or both ends of the door sections, the action providing a toggle lever connection to each door section and having the free ends of the levers pivotally connected to a toggle head, which is advanced by suitable gearing to open the doors and retracted by reversing the gearing, to close the doors.

When the gearing employed is of a type that is self-locking or otherwise locked when not in operation, an additional toggle lock is not required and the advance and retraction of the toggle head to open and close the doors, may be limited to movement within the building or on the inner side of the doorway but with gearing that would be thrown into reverse action by the weight of an open door, the toggle lock may be employed by extending the advance of the toggle head between and beyond the points of attachment of the toggle levers to the doors, where further advance of the head is checked and it is held against movement in either direction. Reversing the gearing retracts the toggle head, which is drawn from its advanced position and its inward movement is continued until the doors are closed.

As the doors, preferably, are relatively weighted to balance each other, they have no free movement and are dependent in opening and closing upon the action of the gearing, which may be of any suitable or well known form.

Other features of the invention not specially mentioned above, will be brought to attention in the detailed description that follows.

2

Several embodiments of the invention are shown in the accompanying drawings but, it will be understood, that no limitations are intended by this showing, other than are imposed by the appended claims.

In the drawings—

Fig. 1 is a front view in elevation of a hangar, showing the entrance closed by doors constructed in accordance with the present invention.

10 Fig. 2 is a partial longitudinal section of the same, taken on the line s^2-s^2 of Fig. 1.

Fig. 3 is a similar view of a modification, and Fig. 4 is a like view of a further modification.

15 Referring now to the drawings, 1 indicates the entrance doorway of a hangar 2, which latter may be of any size and construction desired but is preferably designed to accommodate a single small airplane.

20 As a floor protection against flooding by a heavy rainfall and the entrance-blocking effect of a heavy snowfall, the floor is raised about a foot above the ground level. To bridge the gap between the floor and ground, the concrete foundation is extended forward in the form of blocks 3, spaced apart across the front of the building. These blocks present a downwardly inclined surface, reaching from the floor to the ground, and serve as supports for the lower section 4 of the entrance door, which comes to rest thereon when in open position, as indicated in dotted lines in Fig. 2, and serves as a ramp to ease entrance of an airplane into the hangar.

25 The door closing the entrance to the hangar is divided lengthwise into two sections, the upper section 5 being hinged to the top of the doorway, as indicated at 6, to swing outward and upward about a horizontal axis and the lower section 4, being hinged to the bottom of the doorway, as indicated at 7, to swing outward and downward about a parallel axis.

30 40 The doors may be of any design and construction desired, the upper one ordinarily being provided with a number of windows 8, to admit light to the interior of the building and for ventilation purposes.

45 50 The upper door is preferably of greater height than the lower door and in order to operate them with a minimum amount of power, the lower door is suitably counterweighted to balance the greater weight of the upper door. Thus balanced, they have no independent movement of their own and respond only to the action of the gearing by which they are opened and closed.

55 A toggle action is employed for opening and closing the doors and consists of a pivoted toggle

lever 9 adjustably connected to each door and a movable toggle head 10, to which the free ends of the levers are pivotally connected. As the adjustable connection of the toggle levers to the doors, shown in Figs. 2 and 4, may be of any suitable or well known form, it will not be necessary to describe the same in detail.

The advance and retraction of the head to give the levers the required movement to open and close the doors, that is, from the full line to the dotted line position shown in Fig. 2, is effected by suitable gearing, which may be hand-operated as indicated by the crank 11, shown in Fig. 2, or by power, as indicated by the motor 12, diagrammatically shown in Figs. 3 and 4.

The toggle head in Figs. 2 and 3, is carried by a rack bar 13, movable in guides 14, 14, and is engaged by a pinion 15, the rotation of which by hand, as in Fig. 2 or by power, as in Fig. 3, gives motion to the rack bar to advance and retract the toggle head. Outward movement of the rack bar is limited by the lower door coming to rest on the inclined blocks 3 and to prevent any tendency of the rack bar to be moved rearward by the weight of the upper door, under the force of high winds, for example, a locking pawl 16, is shown in Fig. 2, which may be thrown in and out of engagement with the pinion 15.

In the power-driven gearing shown in Fig. 3, the toggle head is advanced by the rack bar between and beyond the points of connection of the toggle levers to the doors, as indicated in dotted lines, and by the well known toggle action, locks the rack bar against retraction. To prevent further advance of the head by the weight of the upper door, a stop 17 is secured to the inner end of the rack bar which brings up against the rack bar guide when the rack bar is fully advanced.

To insure smooth operation, it may be desirable to duplicate a toggle action shown at the opposite end of the doors, as indicated diagrammatically in dotted lines in Fig. 1. This could be readily done and operated by means of a cross shaft 18 in a floor pit 19, as shown in Fig. 3.

In the modification shown in Fig. 4, the toggle head is advanced and retracted by a motor-driven screw shaft 20, which is self-locking when not in operation.

To avoid opening the main doors to gain entrance to the hangar, a small auxiliary door (not shown) may be provided in either the main doors or the wall of the building.

For operating the power-driven gearing, re-

versible electric motors are preferably employed and control switches 21, are provided either or both inside and outside the building.

As the construction, operation and many advantages of the invention will be clearly apparent from the foregoing, it will not be necessary to further describe the same.

I claim:

1. A closure for a building entrance opening above the ground level and operating means therefor, comprising a pair of doors of balanced weight and different height arranged one above the other and hinged at the top and bottom of the entrance to swing outward in opposite directions about horizontal axes, the upper door being of greater height than the lower door and when open serving as a canopy to protect the entrance against weather conditions and the lower door when open inclining downwardly and resting on the ground as a ramp, a toggle lever connection to each door, a toggle head connecting the levers, gearing for advancing and retracting the toggle head to impart opening and closing movement to the doors through the toggle lever connections, the toggle head being movable by said gearing beyond the line of centers of the toggle lever connections to the doors to lock the doors in open position and against accidental closing.
2. A closure for a building entrance and operating means therefor as defined in claim 1 in which the toggle levers and gearing are duplicated and positioned at opposite sides of the doors, means for connecting the same for simultaneous operation and single means for actuating said connection to thereby simultaneously effect movement of the toggle heads.

CLYDE POTTS.
